UNITED STATES PATENT OFFICE.

JEFFERSON D. MARSHALL, OF NEW ORLEANS, LOUISIANA.

MILL.

1,109,932.

Specification of Letters Patent.

Patented Sept. 8, 1914.

Application filed May 27, 1914. Serial No. 841,178.

To all whom it may concern:

Be it known that I, JEFFERSON D. MARSHALL, a citizen of the United States, and a resident of New Orleans, in the parish of Orleans and State of Louisiana, have invented a new and Improved Mill, of which the following is a specification.

This invention relates to means for resisting the stresses on the upper rolls of three-roll mills, especially of mills for crushing sugar cane, and its object is to provide a mill in which the bolts for resisting these stresses are arranged substantially parallel to the plane connecting the axis of the upper roll with the axis of one of the lower rolls.

This invention consists in a three-roll mill-housing having a slot to receive one of the lower roll-shafts and the upper roll-shaft, together with the bearings therefor, and bolts extending substantially parallel to each other and to the line of thrust of these rolls, from the upper cap down through the base of the housing.

In the accompanying drawing, which is a side elevation of a mill for crushing sugar cane provided with three rolls in triangular relation with their axes parallel, 1 indicates the base upon which the housing 2 is secured in any desired manner, bolts 3 being shown. The shaft 4 of the roll 5 is mounted in a quarter-box 6, and the cap 7, ram 8, and rods 9 may be of the same construction as similar parts in the Bancroft Patent, Number 1,023,355, dated April 16, 1912. It will be understood that a like construction is used for the other side of the mill.

The housing 2 is formed with an inclined slot or pocket 11, in which is mounted the bearing 12, for the shaft 13 of the second lower roll 14. A wedge-plate 15, which may be positioned by the screw 16, supports this bearing.

The lower bearing 17 of the shaft 19 of the upper roll 20 rests on the shoulders 18 and prevents metallic engagement between the rolls 20 and 14. The upper bearing 22 is engaged by the plate 23, and that in turn by the hydraulic ram 24, mounted in the

cap 25, in the manner shown in the Bancroft Patent Number 1,095,067, dated April 28, 1914. The rods 26 may have nuts 27 at their upper ends and keys 28 at their lower ends. They extend substantially parallel to the plane passing through the axes of the rolls 14 and 19, and therefore parallel to the lines of stress between these rolls, through the bed 1, housing 2 and cap 25. The rods 9 extend across through the housing on both sides of the shaft 13 to reinforce it.

The sugar-cane, in the form of short chips, passes to the mill from the right in the drawing, and between the rolls 5 and 20, the distance between these rolls being determined by the ram 8. After this preliminary squeezing, the chips are crushed between the rolls 14 and 20, receiving the full pressure of the upper roll under the force of the hydraulic ram 24, and give up substantially all the extractable juice.

The part 30 of the housing is reinforced by the cap 25 and by the rods 9, so that there is little danger of this part of the housing breaking away. As the shafts 13 and 19 are in the same slot, one cap is saved. As most of the comparatively light stresses, arising from cane passing between the rolls 5 and 20, are taken up by the rods 9, and as all the stresses arising from the cane passing between the rolls 14 and 20 are taken by the rods 26, the housing may be made comparatively light.

I claim:

1. A sugar mill comprising a base, a housing mounted thereon, three crushing rolls and the shafts for the same, said housing having a pocket and an inclined slot, a bearing for one of the roll shafts mounted in the pocket, bearings for the two other roll shafts mounted in said inclined slot, a cap at the upper end of the slot, and bolts extending through the cap, housing and base, parallel to the plane passing through the axes of the shafts in said slot.

2. A sugar mill comprising a housing, three crushing rolls and shafts for the same mounted in triangular arrangement with their axes parallel, said housing having a

slot, bearings for two of the roll shafts mounted in said slot, a cap at the outer end of the slot, and bolts extending through the cap and housing parallel to and on each side of the plane passing through the axes of the shafts in the slot.

In testimony whereof I have signed this

specification in the presence of two subscribing witnesses.

JEFFERSON D. MARSHALL.
